UNITED STATES PATENT OFFICE.

LESLIE S. HALL, OF BRANTFORD, ONTARIO, CANADA, ASSIGNOR TO WILLIAMS TOOL CORPORATION, OF ERIE, PENNSYLVANIA.

PIPE-THREADING MACHINE.

Application filed February 18, 1924. Serial No. 693,604.

My invention relates to machinery and particularly to that type known as a pipe or bolt threading machine. A simple, portable, inexpensive, efficient pipe threading machine 5 has long been sought by tradesmen who in the course of their business require large quantities of pipe to be threaded. The principal object of my invention is to supply a machine answering all the requirements of 10 such demands and containing many features and improvements highly desirable and useful in the art to which they pertain.

One of my objects is to provide a machine of the character described which is light in 15 weight, readily demountable and easy of operation, and which will permit the ready portability thereof, by the user, to one job or another where it may be useful.

Another object is the provision of a new 20 inexpensive and efficient type of ways upon which the head of the machine travels.

Many other objects and advantages in details of construction and operation will be apparent as the description proceeds, reference being had to the accompanying drawings wherein like reference numerals indicate like parts.

Figure 1 is a side view of my improved machine, completely assembled and ready 30 for operation.

Figure 2 is a perspective of the assembled machine showing the back and the side opposite that shown in Fig. 1.

Figure 3 is an exploded side view of a 35 part of the machine showing the demountability of the ways and bed and the controlling lever for the belt tensioning device.

The base of my machine is indicated generally by the reference numeral 1 and as 40 shown, is cut away around its sides as at 2, 3, 4, 5, 6 and 7, (Figs. 1 and 2) in order to both lighten the machine in weight and to permit ready access to the parts and elements contained within the base. A bed 8 is 45 removably mounted on the front of the base in a manner to be described. The upper end 9 of the base 1 is constructed to contain the driving mechanism, and is enclosed by a removable cap or dome 10 secured in place 50 by means of screws 11.

A chuck 12 is mounted at the top of the base 1 and is provided at the rear with the usual centering and steadyng element controlled by the hand wheel 13. This chuck, 55 driven by the motor 30 in the base 1, is of

course adapted to receive and rotate a section of pipe or other element to be threaded, indicated in Fig. 1 at 14.

Extending thru the base 1 are a pair of parallel openings 15 (see Figs. 2 and 3) in which are removably mounted a pair of tubes or rods 16 constituting the ways of the machine. Suitable bearings 17 are provided on the front of the base and set screws 18 in said bearings provide means for securing said ways against movement. The ways 16 when secured in position extend from a point flush with the rear of the base as shown in Fig. 2, thru said base and projecting beyond the front thereof to provide 70 a support for the outer end of the bed 8 and for the head and carriage indicated generally at 19. The bed is provided at its outer end with any suitable securing means as for instance screws or bolts 20, whereby 75 the bed is supported by the outer ends of the ways.

The carriage 19 is slidably supported on the ways 16 by means of bearings 21 resting on top of said ways.

It will be noted by reference to Figs. 1 and 3 that the bed 8 slopes downwardly from its outer end toward the base. The inner end of the bed 8 is provided with a funnel or chute arrangement 47 which fits within an enlarged portion 48 of the base and which when in position, lies directly over the oil reservoir 42. This member 47 accomplishes a two fold purpose, first in providing a support or resting means for 90 the inner end of the bed 8 on the base whereby the bed is securely held in place, and secondly, acts to deliver the used oil back into the reservoir where it is again pumped thru the machine. This end piece 85 47 of the bed is offset or shouldered as at 49 in order to catch any cuttings and prevent them from being fed into the oil reservoir. The lower end of the bed 8 is of course screened at 50 as an additional safeguard against this. The sloping bottom of the bed 8 permits the used oil to readily drain thru the screen and be delivered by the chute 47 into the reservoir.

From the foregoing description it will be seen that I have devised a pipe threading machine containing a new and decidedly useful feature which is of importance in a device of this character and a distinct 100 advance in the art. As was described, the 105

head and carriage, the ways and the bed may be quickly removed from the base which greatly facilitates its ease of transportation.

5 Inasmuch as the operation of the device is obvious from the foregoing description of the various parts, the same will not be repeated here. It will be apparent to those skilled in the art that many changes in 10 details of construction and operation are possible without departing from the scope of the invention. I do not limit myself, therefore, to the exact construction shown and described, other than by the appended 15 claims.

I claim:

1. A threading machine comprising a base, a pair of parallel supports removably mounted in said base and projecting therefrom, a head and carriage slideable on said supports, and a bed beneath said head re-

movably supported at one end by said supports and at the opposite end by said base.

2. A threading machine comprising a base provided with a pair of parallel supports projecting therefrom, a head and carriage slideable on said supports, a hollow boss on said base beneath said supports, a removable bed beneath said head supported at one end by said supports and at the opposite end by said hollow boss.

3. A threading machine comprising a base provided with a pair of parallel supports projecting therefrom, a head and carriage slideable on said supports, a hollow boss on said base beneath said supports, a removable bed beneath said head supported at one end by said supports and at the opposite end by said hollow boss, said bed having a projecting trough receivable in 40 said boss.
